UNITED STATES PATENT OFFICE.

GEORGE H. SPAFFORD, OF CHICAGO, ILLINOIS.

NON-REFILLABLE BOTTLE.

SPECIFICATION forming part of Letters Patent No. 733,293, dated July 7, 1903.

Application filed October 14, 1902. Serial No. 127,279. (No model.)

To all whom it may concern:

Be it known that I, GEORGE H. SPAFFORD, a citizen of the United States, residing at Chicago, in the county of Cook and State of Illinois, have invented certain new and useful Improvements in Non-Refillable Bottles, of which the following is a specification.

This invention relates to certain improvements in non-refillable bottles hereinafter fully described and claimed.

Reference is to be had to the accompanying drawings, which illustrate my invention as applied to two bottles, Figure 1 being a vertical sectional view of a bottle intended for liquid contents, and Fig. 2 being a similar view of a bottle intended for contents of a pulverulent nature.

Referring to the drawings, Fig. 1, the letter *a* designates the body of a bottle provided at its upper edge with an inturned shoulder *a'* and also provided below said edge with a second inturned shoulder *a''*. On said latter shoulder rests a disk *b*, provided with a central spider *b'*, forming apertures *b''*, and immovably secured in said spider is a vertically-extending open tube *c* for a purpose to be presently described. A cylindrical valve-seat *d* is provided with an outwardly-extending flange *d'*, resting on the top of the disk *b* and secured thereto by wax or a suitable cement *d''*, and said valve-seat is located directly above the apertures *b''* and surrounds the upper end of the tube *c*, as shown. Coacting with the valve-seat *d* is a valve *e* of substantially crown shape, provided with a soft-rubber or similar packing *e'*, holes *e''*, below said packing, and a circular outwardly-extending ledge *e''*, which surrounds the cylindrical valve-seat when the valve is resting on the latter, as illustrated in Fig. 1, and a ring-like weight *f* normally surrounds the body of the valve and rests loosely on the ledge thereof to assist the valve to its seat and hold it thereon while the bottle is in the upright position. The valve-seat is preferably made of glass and the valve of wood. The neck *g* of the bottle is constructed separate from the body and is secured thereto by its skirt *g'* being supported on the disk *b*. Cement *h''* is filled in between said skirt and the adjoining wall of the body *a*, and before the cement is allowed to set a cap-piece *h* is inserted over

the neck, said cap-piece being provided with an inwardly-extending shoulder *h'*, which co-acts with the shoulder *a'* of the bottle-body to hold the cap-piece on the body after the said cement has been allowed to set. The interior of the skirt *g'* forms a chamber in which the valve *e* and its seating-weight may move. Within the base of the bottle-neck *g*, where it joins its skirt *g'*, is located a preferably wooden ring *i*, secured by cement setting in corresponding holes *i'* in the ring and neck, and secured in said ring is a second cylindrical valve-seat *j* (an upper valve-seat, 65 in contradistinction to the other valve-seat *d*) of any suitable material and with which co-acts a cap-valve *k*, provided with a soft-rubber packing *k'* and holes *k''*, as shown. Two weights operate in connection with this upper 70 valve *k*. One weight *l* is a disk adapted to rest on the top of the valve when the bottle is upright and said disk provided with marginal passages *l'*, and the other weight is a ball *m*, adapted to rest on the first-named weight 75 when the bottle is upright and also adapted to roll or drop into a recess *n''* in the adjacent surface of a baffle-block *n*, which is preferably made of wood and which swells when wet to fit tightly in the upper end of the bottle-neck *g*. 80 The said block is provided with passages *n'*, and secured to said block is a glass pin *o*, which extends therefrom to the closed top of the neck, and a baffle-ring *p* rests loosely on the top of the block *n*. The bottle-neck is provided just 85 below its closed top with outlet-apertures *g''*. When the bottle is in the upright position, (illustrated in Fig. 1,) it is evident that no liquid can be poured past the upper and lower valves *k* and *e*. When the bottle is inverted, 90 the said valves will move off their seats, and liquid can then flow out through the aperture *b''*, holes *e''*, into the chamber formed by the interior of the neck-skirt *g'*, and thence through the valve-seat *j*, holes *k''*, passages 95 *l'* and *n'*, and outlet-apertures *g''*. While the liquid is flowing out as described air is flowing in through those passages and apertures which are uppermost, according to the tilted position of the bottle, and through the open 100 tube *c* into the body of the bottle. The valves *k* and *e* are both made of wood or other buoyant material, and if an attempt is made to force liquid into the bottle when the latter

is inverted the said valves will float up to close their valve-seats, and thus prevent such an attempt.

The bottle illustrated in Fig. 2 is intended to be used for effervescing powders and similar pulverulent substances and differs from the other bottle just described mainly in that the lower disk q has no central spider, because the air-tube c is not employed, also in the fact that the second or upper valve mechanism is not employed, but one valve is used, and also in the fact that the valve e is provided in its upper surface with a recess e^1 , complementary to the recess n^2 , to receive the ball-weight m .

Both bottles are preferably provided with graduations, as illustrated in the drawings.

Having thus fully described my invention, what I claim, and desire to secure by Letters 20 Patent, is—

1. In a non-refillable bottle, the combination of a valve-seat through which the contents of the bottle must pass; a valve mechanism adapted to control said valve-seat and including a valve carrying a loose weight; a baffle-block above said valve; and a ball-weight interposed between said valve mechanism and said baffle-block, as and for the purpose set forth.

2. In a non-refillable bottle, the combination of a valve-seat through which the contents of the bottle must pass; a valve adapted to control said valve-seat and provided with an outwardly-extending ledge; and a ring-weight loosely supported on said ledge.

3. In a non-refillable bottle, the combina-

tion of a valve-seat through which the contents of the bottle must pass; an air-tube supported within said valve-seat; a valve adapted to control said valve-seat and to open 40 and close said air-tube; and a baffle-block above said valve, as and for the purpose set forth.

4. In a non-refillable bottle, the combination of a disk in the body of the bottle; a cylindrical valve-seat secured in said disk and projecting upwardly therefrom; a crown-valve adapted to seat on said valve-seat and provided with an outwardly-extending ledge; a ring-weight loosely supported on said ledge; 45 a baffle-block above said valve and provided in its lower surface with a recess; and a ball-weight interposed between said valve and baffle-block and adapted to fall into said recess when the bottle is inverted, as set forth. 50

5. A non-refillable bottle, comprising a body provided at its upper edge with a shoulder, a' , and below said edge with another shoulder, a^2 ; a neck provided with a skirt supported by said last-named shoulder and 60 secured thereon by cement; a cap-piece, h , surrounding said neck and resting on the first-named shoulder, a' ; and a valve mechanism in said neck designed to prevent the passage of liquid to the body, as set forth. 65

In testimony whereof I affix my signature in the presence of two witnesses.

GEORGE H. SPAFFORD.
